FLASHLIGHT SWITCH

Fred C. Schultz, Chicago, Ill., assignor to The
Edward Katzinger Company, Chicago, Ill., a
corporation of Illinois

Application August 1, 1941, Serial No. 405,029

6 Claims. (Cl. 200—60)

This invention relates to a flashlight switch and has for its object the provision of a switch which is simple and inexpensive in its construction and adapted for ready assembly.

According to the present invention the improved switch includes a housing or operating member mounted to slide on the outer surface of a battery case, and a switch element secured to the housing for sliding movement internally of the case, and means for locking said switch element in "off" position including a flexible extension which is depressible to release the switch element for movement to "on" position as an incident to movement of the housing toward said "on" position.

The switch element may be depressed by a roller adapted to slide with the housing on the outer side of the case and coacting with the flexible extension by means of an opening in the case through which the roller may be partially projected.

With the above and other objects in view, as will be apparent, this invention consists in the construction, combination and arrangement of parts, all as hereinafter more fully described, claimed and illustrated in the accompanying drawing, wherein:

Fig. 1 is a fragmentary longitudinal vertical sectional view of a flashlight embodying a switch assembly according to the present invention, and shown in "on" position.

Fig. 2 is a similar view showing the switch in "off" position.

Fig. 3 is an elevational view of the parts shown in Fig. 2 when turned through an angle of 90 degrees relative to the position thereof shown in Fig. 2.

Fig. 4 is a detail bottom view of the operating member.

Fig. 5 is a fragmentary detail view of the flashlight case illustrating the arrangement of the apertures cooperating with the operating member contemplated by this invention.

Fig. 6 is a fragmentary detail view of the switch element, including the flexible extension thereof.

Reference being had more particularly to the drawing, 10 represents a tubular flashlight casing of conductive material, such as metal. The switch contemplated by the present invention comprises a housing or operating member 11 in the form of a finger piece having a peripheral flange 12, part of which at each side of the finger piece is slit and bent angularly to provide a pair of opposed guiding arms 13 which extend through suitable apertures 14 in the wall of the case. The

arms 13 have inturned ends adapted to be passed through said apertures and occupy a position at some distance inwardly from the inner surface of the case 10 when the arms 13 are fully projected through said apertures.

Coacting with said operating member 11 to provide an element for opening and closing the lamp circuit is a contact member or strip 16 of brass or similar material, having an extension or shank portion 17 adapted to be interposed between the arms 13. The shank 17, as shown in the drawing, is of a thickness corresponding to the clearance provided between the ends 15 of the arms 13 and the inner surface of the case 10 opposite thereto while the width of the shank is such that the inner surfaces of the arms 13 slidably guide the longitudinal edges of the shank to accommodate entry of the shank therebetween by movement in a path lengthwise thereof. Such insertion of the shank 17 from an entering position to a position wherein a portion of the shank overhangs or projects beyond the limits of the ends 15 of the arms 13 is limited by the abutment of aligned stops or shoulders 18 at the inner end 19 of the shank with the edges of the arms 13. The portion of the shank thus projecting beyond the arms 13 and ends 15 is slit longitudinally as at 20 to provide a pair of aligned tongues 20 normally sprung outwardly from the surface of the shank 17 facing the bearing surface of the ends 15 and presenting transverse edges 21 which engage the edges of the ends 15 at the outlet side thereof to prevent withdrawal of the extension or shank 17 when the shoulder 18 is in engagement with the edges of the arms 13. The resiliency of the tongues permits them to be pressed inwardly toward the plane of the shank during their passage through the space defined by the arms 13, ends 15 and inner surface of the case 10 whereupon the tongues 20, on reaching a position clear of the edge of the ends 15 will spring outwardly and snap into engagement with said edge of the ends 15 to lock the shank 17 against withdrawal from the arms 13.

When so assembled, the operating member 11 and contact strip 16 are rigidly and securely interlocked for movement as a unit in the apertures 14 of the case wall, with the shank or extension 17 slideable against the inner surface of the case opposite the rear end of the operating member.

In the "off" position of the contact strip 16, as shown in Fig. 2, a pair of transversely aligned lugs 22 struck inwardly from the inner surface of the case provide keepers engageable with the edges of notches or recesses 23 formed in the

longitudinal edges of the extension 17. On depressing the extension 17 downwardly (as shown in dotted lines in Fig. 2) the extension is movable to unlocked position relative to the lugs 22 and is prepared to be moved to "on" position by sliding the operating member 11 forwardly, to the position shown in Fig. 1.

For the purpose of facilitating depression of the extension 17 as an incident to the operation of sliding the housing or operating member 11 to "on" position, a roller or spherical member 25 is mounted in the housing 11 for movement therewith as shown in Figs. 1 and 2. An elongated opening in the wall of the case 10 underlying the housing 11 provides a pair of opposed edges 26 extending lengthwise of the path of movement of the housing and tapering inwardly and forwardly from the rearward end thereof. These edges provide guideways on which the lower portion of the roller 25 rides during sliding movement of the housing 11. In the "off" position of the contact member 16 (as shown in Figs. 2 and 3) the roller is so disposed as to coat with the widest part of the edges 26 enabling a portion of the roller to project inwardly of the case. Thus the extension operates to urge the roller outwardly against the rim 28 of an opening in the rearward top surface of the housing 11, through which opening a portion of the roller protrudes for ready access. Accordingly, when the protruding portion of the roller is pressed inwardly of the housing 11, the surface of the extension is acted upon by the roller to move the extension downwardly to clear the lugs 22. When the roller is carried forward toward "on" position, the forwardly tapering edges or guideways 26 of the opening operate to elevate the roller so as to relieve pressure on the extension 16 and prevent flexing thereof when the roller is in such position. By so limiting the flexing of the extension 16, except at such intervals as it is necessary in connection with moving the contact member from "off" to "on" position, the life of the contact member is prolonged.

From the foregoing, it will be apparent that the housing 11 may be wholly preformed and the assembly operation involved in the manufacture and production of the present switch consists merely of placing the roller in the opening 26 and placing the housing 11 over the roller, with the flange 12 resting against the outer surface of the case and the arms 13 extending through the apertures 14 in the case, and then inserting the contact strip through the space between the arms 13 until the tongues 20 engage the rear edge of the ends 15 of the arms 13.

The contact member 16, as shown herein, is adapted to engage at the forward end 30 thereof with a reflector 31 disposed adjacent to the front end of the case and surrounding an electric lamp 32, the circuit through said lamp being closed when the member 16 is in engagement with the reflector. The source of current for the lamp is available, for instance, from one or more dry battery cells 33 adapted to make contact at one end thereof with the rear tip of the lamp under the action of a helical spring 34 interposed between the closed or capped end of the case 10 and the other end of the battery. With such an arrangement the circuit can take place by way of the rear tip of the lamp 32, the battery terminal, the spring 34, the case 10, the operating member 11, the strip 16, the reflector 31 and thence to the side terminal of the lamp 32.

While certain features of the present invention are more or less specifically illustrated, it is to be

understood that various changes in form and proportion may be resorted to within the scope of the appended claims; similarly, that the materials of the several parts employed may be such as the experience and judgment of the manufacturer may dictate or various uses may demand.

What is claimed is:

1. In a flashlight, the combination of a battery case, a housing mounted to slide longitudinally thereof, a roller mounted in said housing and moving therewith, means providing an opening through which said roller is adapted to project partially internally of the case, a switch element secured to said housing and having a flexible extension engaging the portion of the roller projecting internally of the case and urging said roller outwardly of the case, means for locking said switch element in "off" position including interengaging elements on said case and flexible extension from which the element is releasable by depressing the roller, and means for preventing depression of said roller when the housing is moved away from its position corresponding to "off" position of said switch element.
2. In a flashlight, the combination of a battery case, a housing mounted to slide longitudinally thereof, means providing an elongated opening in the path of movement of said housing, a switch element secured to said housing, a roller mounted in said housing and moving therewith, said roller coacting with the edges of said opening to project partially internally of the case at one extremity of the opening and progressively move to a position clear of the inner surface of the case in movement thereof toward the other extremity of the opening, a flexible extension on said switch element engaging the portion of the roller projecting inwardly of the case and urging the roller outwardly of the case and means for locking said switch element in "off" position including interengaging elements on said case and flexible extension from which the element is releasable by depressing the roller.
3. In a flashlight, the combination of a battery case, a housing mounted to slide longitudinally thereof, a roller mounted in said housing and moving therewith, an opening in the case through which said roller is adapted to project partially internally of the case, a switch element secured to said housing and having a flexible extension engaging the portion of the roller projecting internally of the case and urging said roller outwardly of the case, means for locking said switch element in "off" position including a lug struck inwardly from the inner surface of the case engageable with an element on said flexible extension from which the switch element is releasable by depressing the roller, and means for preventing depression of said roller when the housing is moved away from its position corresponding to "off" position of said switch element.
4. In a flashlight, the combination of a battery case, a housing mounted to slide longitudinally thereof, a spherical member mounted in said housing and moving therewith, an opening in the case through which said spherical member is adapted to project partially internally of the case, a switch element secured to said housing and having a flexible extension engaging the portion of the spherical member projecting internally of the case and urging said roller outwardly of the case, means for locking said switch element in "off" position including interengaging elements on said case and flexible extension from which the switch element is releasable by de-

pressing the spherical member, and means for preventing depression of said spherical member when the housing is moved away from its position corresponding to "off" position of said switch element.

5. In a flashlight, the combination of a battery case, a housing mounted to slide longitudinally thereof, a spherical member mounted in said housing and moving therewith, an opening in the case through which said spherical member is adapted to partially project internally of the case, a switch element secured to said housing and having a flexible extension engaging the portion of the spherical member projecting internally of the case and urging said spherical member outwardly of the case, means for locking said switch element in "off" position including interengaging elements on said case and flexible extension from which the element is releasable by depressing the spherical member, and a guideway associated with said opening coacting with said spherical member to obstruct depression of said spherical member when the housing is moved away from its position corresponding to "off" position of said switch element.

6. In a flashlight, the combination of a battery

case, a housing mounted to slide longitudinally thereof, an opening in the case wall in the path of movement of the housing, said opening having edges defining opposed guideways tapering laterally inwardly with respect to the path of movement of said housing, a switch element secured to said housing for sliding movement interiorly of the case and having a flexible extension movable in a path opposite said opening, means for locking said switch element in "off" position including interengaging elements on said case and flexible extension from which the switch element is releasable by depressing the flexible extension, and means coacting with said flexible extension for depressing the latter including a roller movable with said housing and cooperating with the widest portion of said guideways when said housing and switch element are in "off" position to project partially internally of the case and cooperating with the narrowest portion of said guideways when said housing and switch element are in "on" position to recede to a position substantially clear of the inner surface of the case and said flexible extension.
